ABSTRACT OF THE DISCLOSURE

A switch construction having terminal elements with a wire-like contact extending between the terminal elements. An opening is defined by the construction housing for receiving a pin which engages the wire-like contact to hold the contact out of engagement with a terminal element. The pin is removable when subjected to a pulling force whereby the wire-like contact will be moved into engagement with respective terminal elements.

The invention also contemplates a novel disturb switch construction preferably employed in conjunction with the switch construction referred to. The disturb switch has end terminals which engage terminal elements of the other switch construction. The disturb switch includes a coil spring located in spaced-apart relationship relative to a conductive outer wall. A weight is located in the interior of the coil spring so that the application of physical force, for example if the disturb switch is kicked or dropped, will complete contact between the end terminals.

This invention relates to an improved switch construction, particularly designed for military use.

The use of electrical personnel detecting means has previously been suggested. In one detecting system, a plurality of small transmitters are scattered over an area, and when a relatively large body of personnel enter the area, several of the transmitters will be actuated and signals will be sent to a detecting station. Individuals at the detecting station can determine from the frequency of the signals whether the force is large or small. By providing receiving stations at different locations, the individuals receiving the signals can also pinpoint the location of the personnel.

Since a system of the type described requires the use of a very large number of mechanisms, it is desirable to provide as much economy as possible in their production. Thus, the mechanisms should be as simple as possible to simplify assembly and to hold down material cost. Furthermore, the operation of the devices should be relatively basic so that the devices can be located without undue effort.

It is a general object of this invention to provide improved switch means which are particularly suitable for use in conjunction with detecting means for determining the presence of personnel.

It is a more specific object of this invention to provide switch means of the type described which can be economically manufactured and which are characterized by relatively simple operation.

These and other objects of this invention will appear hereinafter, and for purposes of illustration, but not of limitation, specific embodiments of the invention are shown in the accompanying drawings wherein:

FIG. 1 is a vertical sectional view of a switch construction characterized by the features of this invention;

FIG. 2 is a horizontal sectional view taken about the line 2—2 of FIG. 1;

FIG. 3 is a horizontal sectional view taken about the

2

line 3—3 of FIG. 1 and also including a disturb switch construction characterized by the features of this invention;

FIG. 4 is a horizontal sectional view of the disturb switch shown in FIG. 3; and

FIG. 5 is a perspective view of a pin structure utilized in the switch shown in FIG. 1.

The switch construction of this invention generally comprises spaced-apart terminal elements having a spring contact normally urged into contacting relationship with said elements. The construction defines an opening for receiving a pull out pin which, when inserted into the opening, will engage the spring contact and force the contact out of contacting relationship with at least one of the terminal elements. The pull out pin is designed so that quick removal will immediately restore contact to complete a circuit between the terminal elements.

The construction is designed to receive a disturb switch which is provided with terminals engaging terminal ele-

20 ments of the main switch. When the pull out pin is re-
moved, the construction is armed so that the application of physical forces will operate the disturb switch to achieve a signal or to otherwise operate in an electrical circuit.

25 The disturb switch construction, which has separate utility, preferably comprises a coil spring extending between opposed supports. One of the supports includes a terminal in contacting relationship with the spring. A conductive means is located in surrounding relationship relative to the spring, and a second terminal is connected to this conductive means. A weight is located within the confines of the coil spring, and the application of outside forces will cause movement of the weight and corresponding movements of the spring whereby the spring 30 will engage the surrounding conductive member to complete a circuit between the terminals.

35 The switch construction 10 shown in the drawings comprises an outer cap member 12 defining a cylindrical side wall 14. An inner cylindrical wall 16 is supported on a base 18, and the rim 20 of the cap member engages the shoulder 22 defined by the base. An adhesive or other suitable means may be employed for securing these pieces together.

40 The inner cylinder 16 includes a transversely extending supporting wall 24. This supporting wall is located in spaced-apart relationship relative to the disc 26 which is secured to the top wall 28 of the cap member.

45 A pair of terminal elements 30 and 32 extend through openings 34 defined in the base 18. The upper ends 36 and 38 of these terminal elements extend through openings 40 defined by the supporting wall 24.

50 As best shown in FIG. 2, a spring contact 42 is located in the space between the supporting wall 24 and the disc 26. The spring contact defines ends 44 and 46 which normally bear against the ends 36 and 38 of the terminal elements. The spring contact curves around a post 48 which is formed on the supporting wall 24.

55 The top wall 28 defines an opening 50 which is centrally located relative to the construction. A pin 52 is adapted to be inserted into this opening, and through an axially aligned opening 54 defined by the supporting wall 24. The central portion of the supporting wall includes a raised section 56 which serves to define a portion of the opening 54, and which also serves as a spacing means for the center of the supporting wall.

60 The pin 52 (FIG. 5) defines a pointed end 53 which engages a post 55 extending upwardly from the base 18 to limit entry of the pin.

65 When the pin 52 is in place, the central portion 58 of the spring contact 42 will be forced outwardly as shown in FIG. 2. This will cause the end 46 of the contact to

pull away from the end 38 of the terminal element thereby breaking contact between the terminal elements.

In the preferred form of the invention, the pin 52 is pressed into the openings 50 and 54 so that a relatively great force is required to pull the pin out. This arrangement is desired since the switch is considered to be armed when the pin has been removed, and the switch should be designed so that this armed condition will not occur accidentally during handling.

As shown in FIG. 3, the open interior of the switch construction 10 will be provided with a second switch 60. The switch 60 comprises a disturb switch consisting of a conductive outer casing 62 having a terminal tab 64 formed at one end. The opposite end 66 of the casing is beaded for attachment to the flange 68 of insulating member 70. A second terminal 72 comprises an extension of the T-shaped element 74 which terminates on the opposite side of the insulating member. The head of the member 74 engages the end of a coil spring 76 with the other end of the coil spring being held by insulating member 78. A steel ball 80 is located within the open interior of the coil spring.

The coil spring is designed so that, at a position of rest, the spring will be maintained in spaced-apart relationship relative to the surrounding conductive wall 62. The freely movable steel ball will, however, result in movement of the coil spring when outside physical forces result in movement of the switch. For example, if the switch is lying on the ground and is kicked by a person walking over the ground, violet movement of the steel ball will occur resulting in contact of the spring with the wall 62.

In a modified form of the invention, the ball 80 can be eliminated. In such case, the characteristics of the spring 76 must be such that the mass of the spring will be sufficient to result in contact with the wall 62 when the switch is disturbed. A spring material which is relatively heavy and of relatively soft temper may be selected for this application.

With or without the use of a weight within the confines of the spring, the arrangement described provides advantages over previously employed disturb switches. Thus, the instant invention calls for the connection of the ends of the coil spring to the members 74 and 78 so that the spring is, in effect, suspended between these members. In prior arrangements, coil springs have been employed; however, these prior arrangements provided for connection of the coil spring at only one end. The free end of the coil spring would provide contact when the switch was disturbed because of the movement of the free end. These arrangements require extremely careful selection of the springs since the free end of the springs had to be maintained out of contact with the surrounding wall irrespective of the position of the switch housing. With the arrangement of this invention, confining of the coil spring at both ends provides much broader selectivity from the standpoint of spring selection.

In a typical application for the illustrated arrangement, the terminal elements 30 and 32 would be attached to a transmitter. The terminal elements 82 and 84, which are in contact with the disturb switch, would also be connected to the transmitter. It will be appreciated that while the pin 52 is in place, movements imparted to the construction will not operate the transmitter since the contact arm 46 will be out of engagement with the terminal element 38. Similarly, when the pin is removed and when the construction is at rest, the disturb switch will be open so that transmission will not occur.

It will be understood that various changes and modifications may be made in the constructions described which provide the characteristics of this invention without de-

parting from the spirit thereof particularly as defined in the following claims.

That which is claimed is:

1. A switch construction comprising spaced-apart terminal elements, a spring contact having portions thereof normally urged into contacting relationship with said terminal elements, a switch housing including a transversely extending support member and a wall portion in spaced-apart relationship relative to said support member, said spring contact comprising a wire-like element confined between said support member and said wall portion, at least one portion of said spring contact being movable laterally over the surface of said support member, an opening defined by said wall portion and another opening defined by said support member, a pull out pin movable longitudinally relative to said transversely extending support member for insertion into said openings, said pull out pin extending into engagement with said spring contact for forcing said one portion of said spring contact out of contacting relationship with at least one of said terminal elements, and wherein said spring contact is restored to contacting relationship with said terminal elements upon removal of said pull out pin from said construction.

2. A construction in accordance with claim 1 wherein said pull out pin engages an intermediate portion of said wire contact, said terminal elements extending through said support member with the respective end portions of said wire contact being normally urged into engagement with said terminal elements.

3. A construction in accordance with claim 1 comprising an enlarged interior portion, and including a disturb switch confined within said interior portion, said disturb switch including terminal members fixed in contacting position with other terminals of said switch construction, and means for making contact between the terminal members of said disturb switch when said switch construction is subjected to outside physical forces.

4. A disturb switch comprising a coil spring defining an open interior, means supporting said spring at its opposite ends, a conductive wall located in spaced-apart surrounding relationship relative to the exterior surface of said spring, said supporting means comprising a first electrical terminal contacting said spring, a second terminal connected to said conductive wall, means whereby a portion of said spring intermediate said supported ends is maintained in a position of rest out of contact with said conductive wall, a weight located within said spring, means whereby said weight moves said intermediate portion of the spring into direct contact with said conductive wall when said switch is subjected to outside physical forces.

5. A switch in accordance with claim 4 wherein said weight comprises a metal ball freely movable within the interior of said spring.
